DISPLAY SIGNS

Ralph Steven Britton, New York, N. Y., assignor to
Inco Industries Manufacturing Corp., New York, N. Y.,
a corporation of New York

Application December 30, 1957, Serial No. 705,849

7 Claims. (Cl. 40—140)

This invention relates to display apparatus and, more particularly, to a display sign.

It is an object of the present invention to provide a display sign having a plurality of discrete interchangeable elements that have self-contained means for connection to adjacent similar elements, whereby any predetermined arrangement of such elements may be quickly and simply effected.

Another object of the present invention is to provide a display sign having a plurality of discrete interchangeable members that are detachably connected together by means of self-contained fastening elements that engage with complementary portions of each adjacent member, so as to enable any desired arrangement of such members to be connected together without the need for external or auxiliary means.

A further object of the present invention is to provide interchangeable elements for a display sign having self-contained sign supporting means that are automatically masked from view in response to attachment of each such member with the next adjacent member, whereby the sign may be supported upon any stationary object with such supporting means hidden from view.

A still further object of the present invention is to provide novel supporting means for stacking pre-arranged rows of display sign members together so as to provide a composite sign that has self-contained means for supporting engagement with a stationary member of substantially any type.

A more specific object of the present invention is to provide a display sign that is built of detachable and interchangeable elements which may be secured together with a complete absence of any external or auxiliary linking devices, such that the completed sign is completely devoid of any such additional elements that might otherwise detract from the attractiveness and beauty thereof.

Another object of this invention is to provide a sign in which pins or rails function as an easel to support the sign at varying angles and the heads of the pins or rail are so meshed by the sign elements that they are invisible from the front, and locked in place.

All of the foregoing and still further objects and advantages of this invention will become apparent from a study of the following specification, taken in connection with the accompanying drawing, wherein:

Fig. 1 is a perspective view of a sign made in accordance with the present invention.

Fig. 2 is a front elevational view of one of the standard members forming the sign shown in Fig. 1.

Fig. 2a is a cross-sectional view taken along line 2a—2a of Fig. 2.

Fig. 3 is a rear perspective view of the member shown in Fig. 2.

Fig. 4 is a rear elevational view of an auxiliary member.

Fig. 4a is a transverse cross-sectional view taken along 4a—4a of Fig. 4.

2

Fig. 5 is a rear elevational view of an end member of the sign shown in Fig. 1.

Fig. 5a is a transverse cross-sectional view taken along line 5a—5a of Fig. 5.

Fig. 6 is a longitudinal cross-sectional view of certain parts of the sign shown in Fig. 1 and an associated support connected thereto.

Fig. 7 is a transverse cross-sectional view taken along line 7—7 of Fig. 8.

Fig. 8 is a perspective view of a bridge member forming another part of the present invention.

Fig. 9 is a rear elevational view of a plurality of standard members connected in stacked relationship by means of the bridge member shown in Fig. 8.

Fig. 10 is a perspective view of a modified form of adapter used to stack dissimilar sign members together.

Fig. 11 is a perspective view of a stacked arrangement embodying the adapter shown in Fig. 11.

Fig. 12 is a transverse cross-sectional view taken along line 12—12 of Fig. 11.

Referring now to the drawing and more particularly to Figs. 1 to 3 thereof, a display sign 20 made in accordance with the present invention is shown to be partially

made up of standard sign members 22 that are more clearly illustrated in Figs. 2, 2a, and 3. Each such standard member 22 includes a face plate 23 and a laterally outwardly extending L-shaped side extension 25.

A forwardly extending leg 26 of the side extension 25 is provided with spaced countersunk bores 27 that extend perpendicularly therethrough to the rear face 29. The rear face is provided with a pair of laterally spaced apart and parallel pockets 30 which are of substantially the same size and shape as the leg 26.

Thus, when a pair of these standard elements 22 are connected together in the manner shown in Figs. 1 and 8, the rearwardly extending leg 26 of one such member forms a male connecting element that is frictionally received within the outermost female pocket 30 of the next adjacent member. The thickness of the other leg of the L-shaped side extension 25 is accommodated within the recessed end wall 31 so as to provide a flush fit engagement on both the front and rear sides of the connected elements.

In Figs. 4 and 4a of the drawing, auxiliary sign members 33 are shown to include a face plate 34 and a similar L-shaped side extension 36 that has a rearwardly extending leg 37.

A plurality of countersunk bores 38 also extend rearwardly through the leg 37 for purposes hereinafter described. The rear face of each auxiliary element 33 is provided with a single leg receiving pocket 41 and a recessed end wall 42 for accommodating the male fastening elements of the next adjacent sign member.

In Figs. 5 and 5a of the drawing, a still further modified form of sign member 45 in the form of an end or finishing element is shown to include a face plate 47, a single pocket 48 in the rear side thereof, and a recessed end wall 49. These members 45 are primarily intended to form a cap or mask for a laterally outwardly projecting L-shaped side extension of the member at the end of each row of connected sign units. As such, it has no side extension and merely has a single pocket 48 for receiving such leg of the next adjacent sign member, as shown in Fig. 1.

Referring now more specifically to Figs. 6 and 7 of the drawing, it will be noted that attaching elements in the form of pins 50 may be extended rearwardly through either the upper or lower countersunk bores 27, 38, of the standard and auxiliary members 22, 33, respectively, in order to form an easel or base for supporting a complete sign at any desired angle on any desired surface 51. The countersunk bores accommodate the heads of the pins or other similar fastening means, while the overlapping face plate of the next adjacent sign member

masks such pins and countersunk bores, whereby such fastening and attaching means are locked in place and are completely hidden from view. If desired, other types of hangers, pedestals, or securement means may be extended through the countersunk bores for similar purposes, and for supporting such sign on any desired stationary member.

It is also possible to stack rows of such signs in vertically spaced relationship by means of an auxiliary bridge bar 52. This bar has a central cutout 53 that will accommodate the webs of vertically stacked sign members 22 formed by the adjacent pockets 30, as shown in Fig. 9, whereby the formed spaced legs 55, 56 are frictionally receivable within such pockets 30. These legs 55, 56 are of substantially the same size and shape as the legs 26, 37 of the laterally outwardly extending L-shaped side extensions of the standard and auxiliary members 22, 33, whereby they may be received within the innermost such pockets while the outermost pockets are used to receive the legs of the next adjacent sign members in each row.

With further reference now to Figs. 10 to 12 of the drawing, an adapter 57 is shown which can effectively secure dissimilar rows or dissimilar sign members together. For example, any dissimilar sign member 58 having a horizontal web 59 that may be supported upon the top of any of the aforementioned standard or auxiliary members may be positioned in the manner shown in Fig. 11 with the face plate 60 extending forwardly in the same direction as the face plates of the regular sign members. An L-shaped plate 63 having one leg of substantially the same size and shape as the male leg 26 of the standard member 22 is receivable within one of the pockets 30 of any standard member. The other leg of the L-shaped plate 63 extends upwardly and across the adjacent webs as the top and bottom of the main and dissimilar members, while a transversely extending plate 64 that overlies both legs of the L-shaped plate is receivable within the pocket 61 of the dissimilar member and engageable with the top surface of the web 59 of the dissimilar member. It will thus be recognized that this adapter frictionally secures such parts together so that substantially any type of sign may be fabricated from these prepared and detachably interchangeable units.

By furnishing a kit of various numbers of these sign members, bridges, and adapter units, substantially any type of sign may be readily fabricated for display and advertising purposes. The finished sign may be supported upon any desired stationary object through the use of the self-contained and masked countersunk bores by using pins 50 or other suitable hangers. When so displayed, the signs present a completely finished and tailored appearance, are of unique design, and of particularly neat construction.

While this invention has been described with particular reference to the construction shown in the drawing, it is to be understood that such is not to be construed as imparting limitations upon the invention, which is best defined by the claims appended hereto.

Having thus described my invention, what I claim as new and desire to secure by Letters Patent, is:

1. A display sign comprising a plurality of discrete interchangeable members detachably connected together in a row in side by side relationship, each of said members having a front face and rearwardly disposed complementary male and female portions, the male portions of each one of said members being releasably frictionally engageable with the complementary female portion of the next adjacent member, at least one of said male fastening portions having a headed pin extended therethrough for securing said sign upon a stationary object, and said female portion of the member next adjacent to said one male fastening portion overlying the front of and masking the head of said securing means.

2. A display sign as set forth in claim 1, wherein said male portion each comprises a laterally offset bar spaced rearwardly from said front face, and each said female portion comprises a rearwardly opening pocket of a shape similar to the shape of said bar.

3. A display sign as set forth in claim 2, further including means for stacking a plurality of said rows comprising a bridge in the form of a bar having a central cutout defining a pair of similar discrete legs, said bar 10 extending transversely of said rows, and each of said legs substantially corresponding in size and shape to said female pockets of said members, and said legs being releasably and frictionally engaged within transversely aligned ones of said female pockets of said members in 15 said stacked rows.

4. A display sign as set forth in claim 2, further including means for securing a dissimilar sign member having a longitudinal rearwardly facing ledge carried upon said row of members comprising an adapter in 20 the form of a pair of intersecting plates, one of said plates being of substantially L-shape and the other of said plates being of substantially rectangular shape, said other plate being perpendicularly connected to a ledge of said L-shaped plate and being spaced from and overlying the other leg of said L-shaped plate, said other leg of said L-shaped plate being of substantially the same size and shape as and frictionally engaged within said female pocket of one of said members in said row, and said other rectangular plate overlying and frictionally engaging said ledge of said dissimilar sign member.

5. A display sign comprising a plurality of discrete interchangeable elements, each of said elements having self-contained male and female fastening portions for connection to complementary portions of an adjacent 35 similar element, removable headed pins for supporting said sign, said pins extending rearwardly from said male fastening portions, said female fastening portions overlying and concealing the heads of said pins.

6. A display sign as set forth in claim 5, wherein said 40 male fastening portions are releasably frictionally received within a complementary female portion of the next adjacent member.

7. A font of sign indicia members adapted for detachable interconnection in a row in side-by-side relationship to form a display sign, said font comprising a 45 plurality of interchangeable intermediate members, a plurality of auxiliary members, and a plurality of terminal members, each of all of said members having a front face, the front faces of at least the intermediate 50 members bearing indicia, and each of all of the members having means for interengaging with an adjacent member, said means on all but the terminal members having a vertically disposed tongue or tenon extending forwardly from the back of said member in parallel 55 spaced relation to one side edge of said member, each of all of said members having a vertical recess adjacent the other side edge of and extending toward the front of said member and each of said tongues being releasably frictionally engageable with the recess of an adjacent member, said tongues each having at least one bore extending transversely therethrough, a headed pin extending rearwardly through at least one of said bores, its 60 head being concealed and secured in place by the overlying portion of the next adjacent and interfitting member, all of said members being of uniform thickness 65 throughout, and said pins extending rearwardly beyond the back surface of said members to serve selectively as an easel for supporting the display sign in backwardly tilted relation or as means to secure the sign to a vertical support.
